NECKTIE PACKING MEANS

Samuel C. Pulitzer, New Orleans, La.

Application April 27, 1939, Serial No. 270,453

3 Claims. (Cl. 206—7)

This invention relates to improvements in means for packaging neckties.

An object of this invention is to provide a novel manner of packing neckties or the like in a container so as to prevent wrinkling and distortion thereof during shipment.

Another object of this invention is to provide a compact necktie package which will enable a plurality of neckties to be enclosed therein with a maximum of protection from wrinkling and shifting during shipment and to be packed in a smaller space than has been necessary by previous methods.

A further object of this invention is to provide an insert to be placed within a necktie which will aid in retaining the form and shape of the necktie and which will cooperate with the box in which such neckties are placed to permit packaging of said neckties in a manner to prevent shifting and wrinkling or distortion during shipment.

In packaging neckties for shipment it is necessary that inserts be placed therein in order to keep the tie in shape and to facilitate packing and shipping of the tie package. In ordinary practice, the point or tip of the tie may be crushed by striking against the end of the box during shipment, even when the usual type of insert has been placed therein. By my novel insert and manner of packing this objection can be avoided in a simple and efficient manner.

In the drawing the figures illustrate by way of example a suitable embodiment of my present invention, wherein:

35 Figure 1 is an elevation showing the shape and construction of a necktie insert according to my invention.

Figure 2 is a view in perspective showing a container base containing a plurality of neckties with inserts in place.

40 Other purposes and objects of the invention will appear from a more detail description of the drawing wherein similar numerals refer to similar parts in the different views.

45 The insert 1 is a flat form conforming to the shape of the necktie and adapted to be inserted into the broader end of the tie and to fit snugly within the tie so as to maintain said tie smooth and flat. As shown, the insert is adapted for 50 use with ties of the type usually known as "four-in-hand," but may obviously be used with other types of ties constructed so as to permit insertion of the form.

At the broad end of the insert 1, is formed a 55 projection or tab 2 which is shaped and posi-

tioned so as to engage the end of a box in which the necktie with the form in position is placed.

The projection 2 is long enough to extend beyond the point or tip of the tie when the insert is placed therein, and is shaped to fit into one of the end corners of the tie box and engage the end and one side of said box. The form, with its projection, may be made of any flat material, preferably a thin sheet material such as light cardboard.

In Figure 2 is shown a box 3 containing a plurality of ties each with its insert in place. The insert 1, positioned within the necktie 5, is spaced at its end 6 from the box end 4 by means of the tab or projection 2 on the insert.

In the figure as shown a plurality of ties are so placed that the projecting protecting tabs are at opposite ends of the box for each alternate tie. However, if desired, the ties may be placed on top of each other with the projections engaging the same end of the box or in any other desired order. The usual cover, not shown, is provided for box 3. Obviously, any desired number of neckties may be placed within the container depending on the size thereof. This number may be one or more.

The tab 2 is preferably formed integrally with the body of member 1 and the entire insert can be formed in one cutting operation. However, the projection may be formed separately and attached by means of adhesive or the like. This tab, since it projects from the body of the necktie, may perform a desirable function by having advertising or descriptive matter or other indicia placed thereon which is visible at a glance. When the tie is sold, the insert may be permitted to remain in the tie thus serving to retain its shape until ready for use.

By the use of the novel packing means shown it is readily apparent that the neckties may be shipped in a convenient manner, protected from wrinkling and distortion caused during shipment. The tie ends are spaced from the ends of the box and the ties are prevented from shifting, and the entire assembly provides a neat and compact 45 package.

While my description as above stated has been directed to certain specific embodiments of my invention, other variations and embodiments are within the scope thereof, and I do not intend to 50 be limited by the specific subject matter described.

What I claim is:

1. A necktie package comprising a container, at least one necktie therein, and a form retaining insert within each necktie conforming substan- 55

tially to the shape of said necktie, said insert having a projection extending longitudinally thereof beyond the tip of said necktie at its open end engaging the end of said container, and spacing the tip of said necktie and the portion of said insert within said necktie from said end of said container.

2. A form retaining insert for packaging neckties comprising an elongated sheet member ¹⁰ conforming substantially to the shape of a necktie, and means projecting from said insert and be-

yond the tip of the portion conforming to the end of said necktie adapted to engage the end of a container in which the necktie and the insert are to be placed and space said necktie end and the portion of the insert within said necktie from said container end.

3. A necktie package according to claim 1 in which the projection on the insert is so shaped and positioned as to fit into and engage a corner of the container.

SAMUEL C. PULITZER.
